UNITED STATES PATENT OFFICE.

ALISTER KYLE JEFFERSON, OF STRATHFIELD, NEW SOUTH WALES, AUSTRALIA.

WIRE BALE TIE.

1,409,724.

Specification of Letters Patent. Patented Mar. 14, 1922.

Application filed October 31, 1921. Serial No. 511,395.

To all whom it may concern:

Be it known that I, ALISTER KYLE JEFFERSON, a subject of the King of Great Britain and Ireland, and resident of Jersey Road, 5 Strathfield, in the State of New South Wales, Commonwealth of Australia, have invented certain new and useful Improvements in Wire Bale Ties, (for which I have filed application in Australia, No. 17,830, on 10 September A. D., 1920,) of which the following is a specification.

This invention relates to wire ties for wool bales and other bulky packages containing material of a resilient nature and 15 which require great strength in the binding means to prevent the bale or package from bursting.

Wire ties in themselves are not new and various means and devices have been adopted 20 for securing together the ends of the wire constituting the tie.

The object of my invention is to provide a wire tie which may be readily fastened around a bale, in which the pull on the fastening is in a straight line, and the "give" is 25 reduced to a minimum.

A further advantage arising from my invention is that the fastening of the tie ends may be effected without axially twisting the 30 wire, and this is a very important point when handling stiff wire passed around a bale and therefore having little room for manipulation.

My invention consists in a tie composed 35 of a single length of wire bent at one end to the form of an elongated hook, while at the other end it is formed into a loop of sufficient width to allow the said hook end to pass therethrough, the extreme end portion 40 of the wire lying parallel and adjacent to the wire at the base of the loop and on the same side thereof as the point of said hook, and said loop in side elevation being of flat V formation.

45 My invention also consists in a bale tie as aforesaid further characterized in that the hook is kinked so that portion of it lies in a plane slightly inclined to the plane of the adjacent portion of the wire. This construction facilitates the interlocking of the ends.

My invention further consists in a tie as aforesaid, still further characterized in that the wire at the root of the hook is kinked laterally to still further facilitate the interlocking of the ends.

To more clearly describe the invention

reference will now be made to the accompanying drawings in which, Fig. 1 represents perspectively a wire tie constructed according to this invention, and Fig. 2 shows 60 to larger scale the two ends in plan and opposed, while Fig. 3 represents the same in side elevation. Figs. 4 and 5 represent successive steps in the interlocking of the ends, and Figs. 6 and 7 the completed fastening in 65 plan and side elevation respectively.

The tie A illustrated in Fig. 1 has formed at one end a hook B and at the other end a loop C, and at a point D at the hooked end is kinked as shown in Figs. 2, 4, 5 and 6, and 70 said hook is about midway of its length deflected from the normal plane as clearly shown in Figs. 3 and 7.

The loop C is so formed that viewed in side elevation it has the configuration of a 75 flat V as clearly shown in Figs. 3 and 7.

In applying the tie it is bent around the bale in such manner as to bring the hooked and looped ends into opposed position as shown in Figs. 2 and 3. The hook B is then 30 passed through the loop C and is deflected so that the end E of the hook is to one side of the base of the loop C as shown in Fig. 4; this can readily be done while the tie is slack on the bale as when the latter is in a dumping or like press, the kink at D permitting the said disposition of parts with a minimum deflection of the hook end from the straight line.

The end E of the hook is then passed under and to the other side of the base of loop C (as shown in Fig. 5) by simple manipulation of the hook end of the tie, and the hooked and looped ends being pulled in opposite directions by expansion of the bale 35 consequent on the releasing of the pressure exerted thereon by the press, the end E of the hook returns through the loop C until further progress thereof is prevented by the underlocking of the parts, and the fastening is then complete as shown in Figs. 6 and 7.

It will be seen from Figs. 6 and 7 that the wire being bent to the same side to form both the hook and the loop, the pull on the 105 fastening is in practically a straight line, and that the fastening is of such character that no strain short of breaking the wire will cause it to come adrift if the wire used is of the gauge and quality ordinarily used 110 for the purposes to which wire ties are applied.

What I claim and desire to secure by Letters Patent is:—

A bale-tie comprising a wire bent at one end and to one side to form an elongated hook, and bent at the other end and to the same side to form a loop angularly disposed and of sufficient width to permit the said hook to pass therethrough, said hook being bent

on a transverse axis so that portion of it is inclined to the plane of the adjacent portion 10 of the wire and said loop being inclined and arranged at an angle to the wire.

Signed at Sydney this twenty-seventh day of September, A. D. 1921.

ALISTER KYLE JEFFERSON.
